UNITED STATES PATENT OFFICE.

AUGUSTE FRÉROTTE, OF BRUSSELS, BELGIUM, ASSIGNOR TO HENRY SIMON LIMITED,
OF MANCHESTER, ENGLAND, A BRITISH COMPANY.

SCRUBBING, BRUSHING, CLEANING, AND LIKE MACHINES FOR WHEAT AND OTHER
GRAIN.

Application filed May 22, 1928, Serial No. 279,774, and in Great Britain May 20, 1927.

This invention relates to machines for scrubbing, brushing, cleaning or scouring wheat and other grain of the type in which a helix or spiral is rotated in the grain and exerts the desired action thereon. Heretofore such helix or spiral has been provided with bristles thereon pointing radially from its peripheral edge or axially from positions adjacent the periphery.

10 The object of the present invention is to provide for a more efficient cleaning action upon the grain.

The invention consists in making the helix or spiral or a portion of same, of a set-in or dished form or section, that is with a portion adjacent to the periphery set at an angle, the said dished portion being formed or provided with an abrasive or roughened or brush-like surface for effecting the desired scrubbing, 20 cleaning or scouring of the grain.

Referring to the accompanying sheet of explanatory drawings:—

Figure 1 is a sectional elevation representing a machine provided with a helix or spiral constructed in accordance with this invention.

Figures 2 to 5 illustrate modified types of the dished or set-in portions of the helix or spiral.

30 The same reference letters in the different views indicate the same or similar parts.

In one convenient application of my invention, the set-in or dished portion *a* of the helix or spiral may be at an angle of about 35 45° to the remainder of the spiral or the part *b* and may be provided with a scrubbing or like active face *c* of emery or carborundum composition, as in Figure 2, or with each face *c* and *d* of such material as in Figure 3. 40 Or such dished or like portion may be of corrugated, perforated or indented metal.

As a further modification wire or other brush bristles *e* may be secured on each face of the dished or like portion *a* as in the example shown at Figure 4. Or the dished or set-in part *a* may be made of wood or other material (provided with brushes *e* or otherwise) which is attached to the part *b* of the spiral instead of being formed integrally 50 therewith as in the aforesaid example.

With the said arrangement of dished spiral, as the spiral revolves, the front surface of the dished portion which is passing through the grain has a lifting action thereon in addition to a scrubbing action and the back surface of the dished upper part of the spiral which receives the falling grain may also exert an additional scrubbing action thereon.

I do not limit myself to any particular angle of the dished peripheral part of the spiral with relation to the remainder, neither do I limit myself to any particular material or arrangement of such dished part to produce the requisite abrasive action.

What I claim is:—

1. A mill for scouring grain including a cylinder, a helical member mounted axially in said cylinder for rotation therein, said member having a peripheral flange providing an internal scouring surface substantially facing and inclined to the axis of the cylinder and adapted to exert a lifting effect upon the grain incident to rotary movement of the helical member.

2. A mill for scouring grain including a cylinder, a helical member mounted axially in said cylinder for rotation therein, said member having a peripheral flange providing an internal scouring surface substantially facing and inclined to the axis of the cylinder and adapted to exert a lifting effect upon the grain incident to rotary movement of the helical member, and means on said flange for scouring the grain.

3. A mill for scouring grain including a cylinder, a helical member mounted axially in said cylinder for rotation therein, said member having a peripheral flange providing an internal scouring surface substantially facing and inclined to the axis of the cylinder and adapted to exert a lifting effect upon the grain incident to rotary movement of the helical member, and means located on the internal surface of the flange for scouring the grain.

In testimony whereof I have signed my name to this specification.

AUGUSTE FRÉROTTE.
